UNITED STATES PATENT OFFICE.

FREDERICK G. FRANKENBERG AND ALFRED H. SCHWEICKHARDT, OF
ST. LOUIS, MISSOURI.

DESIGN FOR AN EASEL.

SPECIFICATION forming part of Design No. 29,573, dated November 1, 1898.

Application filed August 18, 1898. Serial No. 688,941. Term of patent 3½ years.

To all whom it may concern:

Be it known that we, FREDERICK G. FRANKENBERG and ALFRED H. SCHWEICKHARDT, citizens of the United States, residing in St. Louis, State of Missouri, have invented and produced a new and original Design for an Easel, of which the following is a specification, reference being had to the accompanying drawings.

Figure 1 is a front elevation. Fig. 2 is a side elevation. Fig. 3 is a rear elevation, and Fig. 4 is a horizontal section on the line 4-4 of Fig. 1.

As shown in the drawings, the leading or essential feature consists of the body B, said body comprising the central rectangular portion 3, the portion 4, surrounding the portion 3 and extending forwardly from the edge there-

of, and the portion 5, surrounding the portion 4 and extending outwardly from the forward edge thereof in a plane parallel with the portion 3, the hook 1, extending forwardly from the upper end of the body B, the hooks 2, extending forwardly from the lower end of the body B, the ears 6, extending backwardly from the body B, and the brace 7, extending downwardly and backwardly from between said ears.

We claim—

The design for an easel substantially as herein shown and described.

FRED. G. FRANKENBERG.

ALFRED H. SCHWEICKHARDT.
